(57) **ABSTRACT**

A printer includes a printing part that prints inputted printing information on paper while moving by gravity and supports that support the printing part and the printing medium facing each other so that the printing part is movable in the gravity direction. The printing part corrects the inputted printing information according to a moving distance and a moving speed of the printing part and prints corrected printing information on the printing medium.

1 PRINTER AND PRINTING METHOD

BACKGROUND OF THE INVENTION

1. Field of the Invention

The present invention relates to a printer and a printing method and, particularly, to a printer and a printing method that print information on a printing medium by moving a printing part or a printing medium in the gravity direction.

2. Description of the Related Art

Printers that are placed on a table and make printing by feeding a printing medium such as paper horizontally with respect to a table surface are widely distributed.

As an example of conventional printers, an inkjet printer has a carriage inside, which feeds paper that is set to a paper tray into the printer and then repeats paper feeding and suspension to discharge the paper outside. While the carriage stops feeding the paper, a print head in the printer moves in the scan direction and injects ink through an ink nozzle, thereby making a print on the paper. In this way, conventional printers make printing by repeating the alternate operation of the print head moving and the carriage paper feeding.

An electric motor is generally used as the carriage. The electric motor, however, consumes a lot of electricity and makes lots of noise during operation.

In order to solve this drawback, a printer that does not have a carriage is proposed.

An example of the printer without a carriage is one that has a medium carrier to feed paper as a printing medium in the gravity direction by using gravity efficiently. For example, Japanese Unexamined Patent Application Publication No. 2003-266867 (FIGS. 1 and 2) describes a printer where a printing part (medium processing engine) is supported by hanging against a vertical wall through a suspension bracket and paper moves down through the printing part by its own weight so that the printing part makes a print on the paper.

On the other hand, a printer where a printing part (medium processing engine) moves in the gravity direction to make a print on paper is described in Japanese Unexamined Patent Application Publication No. 62-80076 (FIG. 1).

Since the above printers have no carriage, the printing part performs printing on a printing medium without stopping the printing medium or the printing part. This causes print displacement due to the movement of the printing medium or the printing part during printing.

Particularly in an inkjet printer, a printing medium or a printing part moves in the gravity direction while a print head moves in the scan direction. This causes a printed result on a printing medium to be distorted obliquely.

As described above, the present invention has recognized that, though the techniques described in Japanese Unexamined Patent Application Publication No. 2003-266867 and 62-80076 have achieved elimination of a carriage by making efficient use of the movement of a printing medium or a printing part in the gravity direction, they have a problem that different printing information from original information is printed.

SUMMARY OF THE INVENTION

According to an embodiment of the present invention, there is provided a printer that includes a printing part printing inputted printing information on a printing medium while moving by gravity and a support supporting the printing part and the printing medium facing each other so that one of the printing part and the printing medium is movable in a gravity direction, wherein the printing part corrects the inputted

2

printing information according to a moving distance and a moving speed of one of the printing part and the printing medium and prints corrected printing information on the printing medium.

5 This structure allows accurate printing of original information while efficiently using the movement of a printing medium or a printing part in the gravity direction.

BRIEF DESCRIPTION OF THE DRAWINGS

10 The above and other objects, advantages and features of the present invention will be more apparent from the following description taken in conjunction with the accompanying drawings, in which:

15 FIG. 1A is a schematic front elevation view showing the structure of a printer according to an embodiment of the present invention;

20 FIG. 1B is a schematic side elevation view showing the structure of the printer according to the embodiment of the present invention;

25 FIG. 1C is a cross-sectional view along line IC-IC in FIG. 1A;

30 FIG. 2A is an enlarged front elevation view showing the structure of a position sensor and a position indicator of a printer according to an embodiment of the present invention;

35 FIG. 2B is a cross-sectional view along line IIB-IIB in FIG. 2A;

40 FIG. 3 is a block diagram showing electrical connection of a printing part of a printer according to an embodiment of the present invention;

45 FIG. 4 is a view to describe a way of correcting a printing ink injection time by a print head;

50 FIG. 5 is a view showing a printing process of a printer according to an embodiment of the present invention; and

55 FIG. 6 is a view to describe the movement of a printing paper and a print head on the printing paper in the printing of corrected information.

40 DESCRIPTION OF THE PREFERRED EMBODIMENTS

The invention will be now described herein with reference to illustrative embodiments. Those skilled in the art will recognize that many alternative embodiments can be accomplished using the teachings of the present invention and that the invention is not limited to the embodiments illustrated for explanatory purposes.

50 The structure of a printer according to an embodiment of the present invention is described hereinafter with reference to the drawings.

FIGS. 1A to 1C are schematic views showing the structure of a printer of this embodiment. FIG. 1A is a front elevation view, FIG. 1B is a side elevation view, and FIG. 1C is a cross-sectional view along line IC-IC in FIG. 1A.

55 Referring to FIGS. 1A and 1B, a bracket 13 has a hook 13a, which is hanged on a vertical wall 2 (which is not a component of a printer 1) shown by a dotted line. Supports 12b and 12c are fixed to and project from the upper end and the lower end of the bracket 13.

60 Referring to FIGS. 1A and 1C, both ends of two cylindrical supports 12a are connected and fixed to the supports 12b and 12c.

65 Referring to FIG. 1C, a printing part 11 has through-holes 11a that correspond to the cylindrical supports 12a. The printing part 11 is supported by the supports 12a, 12b and 12c so that it is movable in the gravity direction.

Further, a print media mount 14 is fixed to the supports 12a and 12c so as to be parallel with the supports 12a.

The supports 12a, 12b, 12c, and the print media mount 14 are formed of a metal material such as iron or a resin material such as plastic.

A holder 15, which is not a component of the printer 1, holds paper 3 as a printing medium against the print media mount 14.

The printing part 11 has a print head 11b that injects printing ink at predetermined time intervals. The print head 11b is movable inside the printing part 11 in the direction of an arrow B, which is a scan direction, shown horizontally in FIG. 1C.

A position sensor 16 detects the position of the printing part 11 by using a position indicator 17. The position sensor 16 is held by the printing part 11 and moves accompanying the movement of the printing part 11. FIG. 2 shows the specific structures of the position sensor 16 and the position indicator 17.

A printing part receiver 18 supports the printing part 11 that moves down along the gravity direction during printing so that it does not fall off the printer 1. The printing part receiver 18 is formed of a cushion material, for example.

FIGS. 2A and 2B are enlarged views showing the structure of the position sensor and the position indicator of the printer according to this embodiment. FIG. 2A is a front elevation view and FIG. 2B is a cross-sectional view along line IIB-IIB in FIG. 2A.

Referring to FIGS. 2A and 2B, the position sensor 16 is composed of a LED 16a that emits light and a photodiode 16b that receives light. The position indicator 17, which has light transmittance, is placed between the LED 16a and the photodiode 16b. Signal lines S1, S2 and GND of the position sensor 16 are connected to a controller (not shown) in the printing part 11 by distribution cables, for example. The position sensor 16 operates with power supply from the printing part 11. The position indicator 17 is configured by applying light-shielding coating at predetermined intervals on the surface of a transparent member 17a such as a transparent tape. The part coated with the light-shielding coating is a light-shielding portion 17b.

The position sensor 16 and the position indicator 17 may be ones that are used for a normal printer.

When a voltage is applied to the LED 16a from the controller (not shown) of the printing part 11 through the signal line S1, the LED 16a emits light toward the photodiode 16b, which is in the direction D. The photodiode 16b detects light from the LED 16a. The photodiode 16b does not detect light when the position sensor 16 passes through the light-shielding portion 17b. The photodiode 16b outputs the light detection as a detection signal to the printing part 11 through the signal line S2.

The printer 11 has a counter (not shown), which counts the number of detection signals supplied from the photodiode 16b.

The printing part 11 calculates a moving distance of the printing part 11 from the counted number of detection signals in the photodiode 16b. Further, the printing part 11 calculates a moving speed from the counted number of detection signals in the photodiode 16b, a measuring time by a timer, and so on.

Now, the electrical connection of a printing part of a printer according to an embodiment of the present invention is described hereinafter with reference to the drawings.

FIG. 3 is a block diagram showing the electrical connection of the printing part of the printer according to this embodiment.

Referring to FIG. 3, a memory 11c stores printing information inputted by a personal computer (PC; not shown) that is connected to the printer 1.

A counter 11d counts a detection signal from the position sensor 16.

A timer 11e measures a time from the start of printing.

A position/speed calculator 11f calculates a moving distance and a moving speed of the printing part 11 in the gravity direction. For example, the moving distance of the printing part 11 is calculated by multiplying a count number of the counter 11d by a distance between the light-shielding portions 17b of the position indicator 17. The moving speed of the printing part 11 is calculated each time a detection signal from the position sensor 16 is input to the counter 11d. For example, it is assumed that the upper end of the position indicator 17 of the printing part 11 is a reference and the number of light-shielding portions 17b of the position indicator 17 is n. It is also assumed that a distance from the upper end of the position indicator 17 when the printing part 11 passes the light-shielding portion 17b at the n-th position from the upper end of the position indicator 17 is y(n), which is positive when falling downward, and a time that the printing part 11 moves from the upper end of the position indicator 17 to the n-th light-shielding portion 17b is t(n). In this case, a moving speed v(n) of the printing part 11 at y(n) may be approximately calculated as follows:

$$v(n) = \{y(n) - y(n-1)\} / \{t(n) - t(n-1)\} \quad \text{Formula 1;}$$

A correction table 11g stores correction coefficients α and β that are correction information to correct printing information according to the moving distance and the moving speed of the printing part 11 so as to accurately print the data of printing information that is inputted by a PC. The correction table 11g may be Random Access Memory (RAM) or Read Only Memory (RCM) that are used for a normal printer.

If the number of print dots from the upper end of the position indicator 17, which is a reference, is i, for example, the following formula may be used to correct the printing information that is inputted by PC in order to print it accurately. If a distance from the upper end of the position indicator 17 (reference) to the i-th print dot is y(i), a moving speed of the printing part 11 at y(i) is v(i), and correction coefficients are α and β , a distance y(i+1) to the (i+1)th print dot is calculated as follows:

$$y(i+1) = y(i) + \alpha * v(i) * [t(i+1) - t(i)] + \beta \quad \text{Formula 2;}$$

The v(i) maybe substituted by v(n) where y(i) $\approx$ y(n), for example. The correction coefficients α and β are determined by comparing original printing information inputted by PC with printed results of the printing information before correction and analyzing printing displacement and print dot interval displacement. Data of the correction coefficients α and β is accumulated in the correction table 11g by repeating test printing a large number of times, which allows reduction of manufacturing variation in the printer, for example. The correction coefficients set in the above formula is just an example, and they are not limited thereto.

For example, it is feasible to change the friction coefficient of the surfaces of the supports 12a so that it becomes higher toward the bottom in order that the moving speed of the printing part 11 is constant. In this case, a load of the printing part 11 in the gravity direction, a reaction force that the printing part 11 receives from the surfaces of the supports 12a and so on are measured at each point of measurement of a moving distance, and the friction coefficient is set for each point of measurement.

5

A print data generator **11h** corrects the inputted printing information by using the correction coefficients α and β that are stored in the correction table **11g** and also corrects a printing ink injection time of the print head **11b** (formula not presented herein) through a controller **11j**. The print data generator **11h** thereby generates corrected printing information and stores it temporarily.

A method of correcting a printing ink injection time of a print head is described hereinafter with reference to the drawings.

FIG. 4 is a view to describe a way of correcting a printing ink injection time by a print head.

Referring to FIG. 4, i and j represent the number of print dots from the upper end of the position indicator **17** as a reference, and they satisfy $j > i$. They thus satisfy $y(j) > y(i)$, and a moving speed that the printing part **11** passes through $y(j)$ is higher than a moving speed that it passes through $y(i)$ since acceleration of gravity is applied longer. Therefore, if the print head **11b** injects printing ink in $y(i)$ and $y(j)$ at the same time intervals, a distance between print dots differs to cause distortion in printed results.

For example, it is assumed that the moving speed that the printing part **11** passes through $y(j)$ is twice the moving speed that it passes through $y(i)$. Then, it can be approximately calculated as:

$$|y(j+1)-y(j)| \approx 2 * |y(i+1)-y(i)| = |y(i+2)-y(i)|$$

Further, it is assumed that, during each of time periods from when the printing part **11** prints a print dot **P1** to when it prints a print dot **P2** and from when it prints a print dot **P2** to when it prints a print dot **P3**, the printing head **11b** once goes and returns the paper **3** shown in FIG. 4 in the width direction. If the moving speed of the print head **11b** in the scan direction (the direction **D** in FIG. 1C and the direction **E** in FIG. 4) is constant, the printing head **11b** once goes and returns the paper **3** shown in FIG. 4 in the width direction during a time period between printing of a print dot **P4** and a print dot **P5**.

In this case, in order to equalize a distance between print dots at $y(i)$ and $y(j)$, the print head **11b** may stop injecting printing ink while the printing part **11** moves from $y(i)$ to $y(i+1)$, for example. It is assumed here that $|y(j+1)-y(j)| \approx |y(i+2)-y(i)|$. In this way, the print dot **P2** in FIG. 4 is not printed, thus allowing the distance between print dots to be the same at $y(i)$ and $y(j)$.

A printing ink injection time of the print head **11b** is thereby corrected in accordance with the moving speed of the printing part **11**, for example.

Referring back to FIG. 3, a print head driver **11k** generates control information of image data to be injected by the print head **11b** and transmits the generated image data control information to the print head **11b**.

A print head motor driver **11n** controls the operation of the print head **11b** in the direction **B** in FIG. 1C and transmits operation control information to a print head motor **11m**.

The controller **11j** controls all the components shown in FIG. 3. The controller **11j** determines a printing ink injection time and an injection position of the print head **11b** and a print head drive waveform based on corrected printing information that is generated in the print data generator **11h**. According to this determination, the controller **11j** supplies a print command signal to the print head motor driver **11n** through the print head motor driver **11n** and also supplies a print command signal to the print head **11b** through the print head driver **11k**.

A printing process of a printer according to an embodiment of the invention is described hereinafter with reference to the drawings.

6

FIG. 5 is a view showing a printing process of a printer of this embodiment.

Referring to FIGS. 1, 2, 3 and 5, after the printer receives printing information from PC, the printing part **11** moves in the gravity direction upon start of printing. As the printing part **11** moves, the position sensor **16** also moves in the gravity direction. While moving in the gravity direction, the position sensor **16** outputs a detection signal each time the photodiode **16b** receives light from the LED **16a** (ST501).

Then, the counter **11d** counts the number of detection signals inputted from the position sensor **16** (ST502).

The timer **11e** measures a time from the start of printing (ST503).

The position/speed calculator **11f** calculates a moving distance of the printing part **11** from a count number inputted from the counter **11d** and further calculates a moving speed of the printing part **11** from the moving distance and a time inputted from the timer **11e** through the controller **11j**. Then, the controller **11j** feeds back the calculated moving distance and moving speed from the correction table **11g** and extracts correction coefficients α and β corresponding to the moving distance and moving speed (ST504).

Then, the controller **11j** performs expectancy operation including a print position of a dot and an injection time of printing ink and corrects printing information to generate corrected printing information (ST505).

After that, the controller **11j** specifically determines a printing ink injection time and an injection position of the print head **11b** and a print head drive waveform and so on from the corrected printing information that is generated in the print data generator **11h**. According to this determination, the controller **11j** supplies a printing command signal to the print head motor **11m** and the print head **11b**, and the print head **11b** prints the corrected printing information on the paper **3** (ST506).

FIG. 6 shows the result of printing by the printer **1**. FIG. 6 is a view to describe the movement of a printing paper and a print head on the printing paper when corrected printing information is printed.

Referring to FIG. 6, arrows **F** to **K** indicate the moving direction of the print head **11b** when printing. Though the arrows **F** to **K** are not all parallel actually, FIG. 6 illustrates them being parallel to each other for simplification.

The printing information is images of a sun **21** and a plurality of flowers **22**. The printer **1** of this embodiment performs expectancy operation of the moving direction of the print head indicated by the arrows **F** to **K** based on the moving distance and moving speed of the printing part **11**, the correction coefficients as correction information stored in the correction table and so on. Then, the printer **1** corrects the inputted printing information and prints the corrected printing information. It is thereby possible to print the original printing information accurately without distortion of a printed image as shown in FIG. 6.

As described in the foregoing, the present invention provides a printer and a printing method that allow accurate printing of original printing information.

Although the above embodiment takes paper as an example of the printing medium, the printing medium is not limited to a two-dimensional object such as paper and a three-dimensional object may be used.

Further, though the above embodiment describes the case where the printer **1** holds the paper **3** unmovingly and moves the printing part **11** in the gravity direction, the present invention

tion may be also applied to the case where the printer 1 holds the printing part 11 unmovingly and moves the paper 3 in the gravity direction, as described in Japanese Unexamined Patent Application Publication No. 2003-266867.

Furthermore, though the above embodiment describes the inkjet printer as an example, the present invention is also applicable to thermal-transfer printers and laser printers, for example.

It is apparent that the present invention is not limited to the above embodiment that may be modified and changed without departing from the scope and spirit of the invention.

What is claimed is:

1. A printer comprising:

a printing part printing inputted printing information on a printing medium while the printing part moves by gravity;

a support supporting the printing part and the printing medium facing each other so that one of the printing part and the printing medium is movable in a gravity direction;

a light emitter moving together with the printing part; a light receiver placed facing the light emitter and moving together with the printing part;

an indicator with light transmittance placed between the light emitter and the light receiver and having a plurality of light-shielding portions arranged in a gravity direction at predetermined intervals;

a counter counting the number of times that the light receiver receives light from the light emitter; and

a timer measuring a printing time, wherein the printing part corrects the inputted printing information according to a moving distance and a moving speed of one of the printing part and the printing medium and prints corrected printing information on the printing medium, and

wherein the moving distance is calculated based on a count value of the counter, and

the moving speed is calculated based on the count value of the counter and a printing time measured by the timer.

2. A printer comprising:
a memory storing inputted printing information;
a printing part printing the printing information on a printing medium while the printing part moves by gravity;
a holder holding the printing medium;

a support supporting the printing part and the printing medium facing each other so that the printing part is movable in a gravity direction;

a calculator calculating a moving distance and a moving speed of the printing part; and

a correction table storing correcting information that corrects the printing information stored in the memory according to the moving distance and the moving speed of the printing part;

wherein the printing part corrects the printing information stored in the memory by using the correction information stored in the correction table and prints corrected printing information on the printing medium.

3. The printer according to claim 2, comprising: a light emitter moving together with the printing part;

a light receiver placed facing the light emitter and moving together with the printing part;

an indicator with light transmittance placed between the light emitter and the light receiver and having a plurality of light-shielding portions arranged in a gravity direction at predetermined intervals;

a counter counting the number of times that the light receiver receives light from the light emitter; and

a timer measuring a printing time, wherein the moving distance is calculated based on a count value of the counter, and

the moving speed is calculated based on the count value of the counter and a printing time measured by the timer.

4. The printer according to claim 2, wherein

the printing part comprises a print head ejecting printing ink, and

the print head ejects the printing ink according to a moving distance and a moving speed of the printing part.
